(57) **CLAIM**

The ornamental design for an insertion tool for spark plug ports and other tubular objects, as shown and described.

DESCRIPTION

FIG. 1 is a top perspective view of an insertion tool for spark plug ports and other tubular objects according to the present invention.

FIG. 2 is a bottom perspective view of the insertion tool for spark plug ports and other tubular objects of FIG. 1.

FIG. 3 is a bottom view of the insertion tool for spark plug ports and other tubular objects of FIG. 1.

FIG. 4 is a top view of the insertion tool for spark plug ports and other tubular objects of FIG. 1.

FIG. 5 is a side view of the insertion tool for spark plug ports and other tubular objects of FIG. 1; and,

FIG. 6 is an alternative perspective view of the insertion tool for spark plug ports and other tubular objects of FIG. 1, showing the tool inserting a spark plug port into an automobile engine.

The broken line showing of the automobile engine in FIG. 6 illustrates the environment of the claimed design and forms no part thereof.

1 Claim, 5 Drawing Sheets
